UNITED STATES PATENT OFFICE.

JOSEPH AMATO, OF NEW YORK, N. Y.

COMBINED TROUSERS-STRETCHER AND COAT-HANGER.

1,080,402.

Specification of Letters Patent.

Patented Dec. 2, 1913.

Application filed March 26, 1912. Serial No. 686,242.

To all whom it may concern:

Be it known that I, JOSEPH AMATO, a citizen of the United States, residing at New York, in the county of New York and State 5 of New York, have invented new and useful Improvements in Combined Trouser-Stretchers and Coat-Hangers, of which the following is a specification.

This invention relates to garment holders 10 and more particularly to combined trousers and coat hangers.

One of the principal objects of the invention is to provide a simple and efficient device upon which a coat may be hung and 15 wherein each separate leg of the trousers may be stretched to any required degree.

Further objects of this invention will appear as the following specific description is read in connection with the accompanying 20 drawing, which forms a part of this application, and in which:—

Figure 1 is a side elevation. Fig. 2 is a top plan view. Fig. 3 is a bottom plan view. Fig. 4 is a vertical sectional view showing 25 the trousers in place thereon.

Referring more particularly to the drawing, 1 represents a tubular rod which has connected to its outer end a bar or head 2 extending upon opposite sides thereof and 30 braced to the rod by means of the struts 3. Slidably mounted in the rod 1 is a rod 4 having a head 5 connected thereto and extending on opposite sides of the same, the head 5 being braced to the rod 4 by means of 35 the struts 6. The rod 4 is provided with a rack 7 which is adapted to be engaged by the spring pressed pawls 8 arranged upon opposite sides of the tubular rod 1. It will thus be seen that by pulling the rod 4 out 40 of the rod 1 that the relative separation of the head 5 may be properly controlled.

The head 2 has arranged upon opposite sides thereof clamping plates or bars 9 and 45 10 which are held in place by bolts 11 having wing nuts 12 arranged thereon. The head 5 has similar clamping bars or plates 13 and

14 mounted upon opposite sides thereof and held in place by the bolts 15 which are also provided with the wing nuts, as shown. The upper edge of the bars 13 and 14, as 50 well as the head 5, is curved so as to provide a shoulder receiving surface which assures a proper hanger to the coat and the member 13 carries a hook 16 by which the device may be suspended. 55

In practice, the wing nuts on the bolts 11 and 15 are loosened at one end of the plates 9—10 and 13—14 and the legs of the trousers inserted between the plates and the bars, the legs of the trousers being arranged upon opposite sides of the heads 2 and 5, as shown in Fig. 4. The plates are then clamped upon the trousers legs and the heads 2 and 5 separated by pulling the red 4 out of the tubular rod 1. 65

What is claimed is:—

1. A device of the class described comprising a pair of telescoping members, means to hold said members in adjusted position, heads carried by said members, one 70 of said heads being arranged to receive a coat, clamping plates arranged upon opposite sides of the heads, certain of said plates conforming to the coat receiving head, and a supporting device secured to one of the 75 clamping plates.

2. A device of the class described comprising a pair of telescoping members, means to hold said members in adjusted position, heads carried by said members, one of said 80 heads being arranged to receive a coat, means to brace the heads and the members, plates arranged upon opposite sides of the heads, certain of said plates conforming to the coat receiving head, clamping bolts extending through the plates and heads, and a supporting hook carried by one of the plates. 85

JOSEPH AMATO. [L.S.]
